R. Hamilton

His ATTORNEY.

UNITED STATES PATENT OFFICE.

MARVIN G. FLEMING, OF KANSAS CITY, KANSAS.

TYPE CABINET.

Application filed May 12, 1922. Serial No. 560,490.

To all whom it may concern:

Be it known that I, MARVIN G. FLEMING, a citizen of the United States, residing at Kansas City, in the county of Wyandotte and State of Kansas, have invented a certain new and useful Improvement in Type Cabinets, of which the following is a specification.

My invention relates to improvements in type cabinets.

One of the objects of my invention is to provide a novel type cabinet adapted to hold type in compact form and for ready removal at one time of a number of type carried in holders.

A further object of my invention is to provide a type cabinet of the kind described, which is simple, cheap to make, durable, not liable to get out of order, which permits the easy insertion and removal of type, and which is adapted for easy transportation.

Still another object of my invention is to provide a novel type holder adapted to hold a bunch of type in compact form and which can be quickly and easily filled with or emptied of type.

The novel features of my invention are hereinafter fully described and claimed.

In the accompanying drawing, which illustrates the preferred embodiment of my invention,

Fig. 1 is a perspective view of my improved cabinet, some of the compartments thereof being filled.

Fig. 2 is an enlarged top view, partly broken away, of my improved cabinet.

Fig. 3 is a reduced vertical sectional view on the line 3—3 of Fig. 2.

Fig. 4 is a perspective view of a bunch of type shown mounted in one of my improved holders.

Fig. 5 is a perspective view of my improved type holder.

Similar reference characters designate similar parts in the different views.

The type cabinet is a case comprising a horizontal base 1 to which is secured the lower end of a vertical member 2, provided on opposite sides respectively with vertical grooves 3, which at their lower ends connect and register with transverse grooves 4 respectively, provided in the upper side of the base 1.

5 designates vertical partition plates, the lower ends of which are respectively mount-

ed in the grooves 4, and the rear edges of which are respectively fitted in the grooves 3. Each plate 5 is T-shaped in horizontal section, the heads of the T's being at the outside of the case and spaced apart to form between them vertical slots or openings 6 provided at the front sides respectively of vertical compartments formed by the plates 5 in connection with the base 1 and vertical member 2. Removably fitted in these compartments and adapted to be disposed there-in one upon the other, are U-shaped type holders 7, Figs. 4 and 5, each of which is adapted to contain a bunch of type 8, the latter being mounted one upon the other between and transversely to the arms of the holders 7. The latter are adapted to be mounted one upon the other in the different compartments, with one set of arms disposed across the openings 6, as shown in Figs. 1 and 2.

For holding the partition plates 5 from vertical movement in the grooves 3, there may be secured to the upper end of the member 2 a horizontal plate 9, which extends over the upper edges of the plates 5, and which has the same width as the thickness of the member 2. For convenience in transporting the cabinet, there may be secured to the top of the plate 9, a central handle 10.

For holding the plates 5 from moving outwardly in the grooves 3 and 4, I provide two horizontal plates 11, disposed at opposite sides of the case and bearing against the outer sides of the adjacent plates 5, adjacent to the upper ends thereof.

Two transverse bolts 12, each provided with a nut 13, extend through the plates 11, and hold the latter tightly clamped against the plates 5.

For completing the end compartments, there are provided two vertical channel plates 14, secured respectively to the vertical ends of the member 2. The flanges of the plates 14 extend inwardly and are spaced apart from the heads of the adjacent plates 5.

The base 1 may be supported in a raised position by a rectangular wire frame having two inverted U-shaped portions 15, secured to the under side of the base 1, transversely thereto. Extending outwardly from the lower ends of the portions 15 are lateral arms 16 which respectively connect with

the lower ends of the arms of two inverted U-shaped portions 17, the horizontal portions of which are disposed longitudinally and upon which may be hung empty U-shaped holders 7.

In the operation of my invention, holders 7 filled with type, are placed one above the other in their proper compartments, which may be designated by characters corresponding to the type contained in said compartments, which characters may be applied, as shown in Fig. 1, to the outer side of the adjacent plate 11, respectively in alignment with the openings or slots 6.

15 When the holders 7 are slipped into the compartments, they are disposed with the arms of the holders in the vertical planes respectively of the openings 6.

When it is desired to extract type from the cabinet, a pointed instrument is inserted through the opening 6 of the compartment which contains the type desired, the instrument being inserted between the two uppermost holders 7. Upon then lifting the instrument, the uppermost holder 7 is raised at its upper end above the plates 5 and 9, upon which it can be grasped by the operator, and wholly removed from the cabinet, after which the type may be removed from the holder thus detached for use, as desired.

With my improved cabinet, the type are stored in compact space and in a manner convenient for ready extraction a considerable number at a time.

35 I do not limit my invention to the structure shown and described, as many modifications, within the scope of the appended claims, may be made without departing from the spirit of my invention.

40 What I claim is:-

1. In a type cabinet, a case having a compartment open at its upper end and provided in its front wall with a vertical slot, and type holders adapted to be removably fitted one above the other in said compartment

ment and accessible through said slot, substantially as set forth.

2. In a type cabinet, a case having a plurality of parallel compartments, each open at its upper end and provided in its front wall with a vertical slot, and type holders adapted to be removably fitted one above the other in each of said compartments and accessible through and registering with the slot in said compartment wall, substantially as set forth.

3. In a type cabinet, a case having a compartment open at its upper end and provided in its front wall with a vertical slot, and U-shaped type holders removably fitted one upon the other in said compartment and accessible through and registering with said slot, substantially as set forth.

4. In a type cabinet, a case having a compartment open at one end and closed at its other end and having a longitudinal opening extending from its closed end, and U-shaped type holders removably fitted one upon the other in said compartment, one set of arms of said holders being disposed at the rear of and wider than said opening, substantially as set forth.

5. In a type cabinet, a case having a compartment open at one end and closed at the other end and having a longitudinal opening extending from its closed end, and a U-shaped type holder removably fitted in said compartment and having one of its arms registering with said opening, substantially as set forth.

6. In a type cabinet, a case having a compartment open at its upper end and closed at its lower end and having a vertical front opening extending from its lower end, and a type holder having a bottom portion for supporting type extending across said opening, substantially as set forth.

In testimony whereof I have signed my name to this specification.

MARVIN G. FLEMING.
